UNITED STATES PATENT OFFICE.

RAYMOND L. KIRKPATRICK AND ANTHONY MOLTHEN, OF CHICAGO, ILLINOIS.

MORTUARY BOARD.

1,237,055.

Specification of Letters Patent. Patented Aug. 14, 1917.

Application filed October 25, 1916. Serial No. 127,529.

To all whom it may concern:

Be it known that we, RAYMOND L. KIRKPATRICK and ANTHONY MOLTHEN, citizens of the United States, and residents of the city of Chicago, in the county of Cook and State of Illinois, have invented certain new and useful Improvements in Mortuary Boards; and we do hereby declare that the following is a full, clear, and exact description of the same, reference being had to the accompanying drawings, and to the numerals of reference marked thereon, which form a part of this specification.

Heretofore, difficulty has been experienced where sudden or unexpected fatalities have occurred, in handling the corpse, and it has been the general practice of morticians to use a basket for the purpose, especially in emergency calls, or in any case of transferment of a remains from place of death to undertaker's morgue.

It is a very difficult matter to handle a corpse without some sort of carrying means, and a basket is not only cumbersome and inconvenient for the purpose, but is generally an unsightly and gruesome object. Furthermore a basket is an odorous and unsanitary means, and requires two men to convey it in every instance, whereas the board forming the subject matter of our invention is clean and sanitary, is disguised by the flaps thereon when being carried from place to place for use and can be easily handled without a body thereon by one person.

Our invention contemplates a flat strong and light board for the purpose, provided with suitable hand holes and with means for strapping the body secure thereto and as well covering the same by suitable flaps for the purpose. It is an object therefore of this invention to construct a mortuary board provided with sanitary fabric flaps and straps, and with means for carrying the board in a convenient manner.

It is also an object of this invention to construct a mortuary board consisting of two thicknesses of the same or different material, with reinforcing members interposed therebetween, and with inner and outer glazed fabric flaps attached on the sides and ends of the board adapted to be folded around a body strapped thereon so as to completely inclose and conceal the body, and with hand holes provided in the sides and

ends of the board for convenience in transporting the same with the body thereon.

It is also an object of this invention to construct a mortuary board consisting of two layers of material secured to one another with reinforcing means therebetween, and with a covering of a washable glazed fabric material, or, if preferred, an enameled metal, on the top surface of the board, and with straps secured between the two thicknesses of which the board is constructed, and adapted to be buckled around the body to hold the same thereon, together with flaps of glazed fabric adapted to be folded over the body to conceal and confine the same upon the board so that handling thereof is facilitated.

It is furthermore an important object of this invention to construct a mortuary board having a surface of glazed material and with a movable pneumatic head rest mounted at one end thereof together with straps for strapping a body upon the board and with flaps adapted to be folded over the body and buckled around on the exterior so that the body is held secured to the board and completely covered by the flaps folded thereover.

It is finally an object of this invention to construct a simple, durable, sanitary, light and portable mortuary board with means for securing a body thereto and completely covering the same, with all the parts and elements thereof readily accessible for cleaning, and, if necessary, easily replaced.

The invention (in a preferred form) is illustrated in the drawings and hereinafter more fully described.

On the drawings:

Figure 1 is a bottom plan view of a device embodying the principles of our invention.

Fig. 2 is a side elevation thereof, with a body secured thereon, and with the flaps folded thereover.

Fig. 3 is a detail section taken on line 3—3 of Fig. 1.

Fig. 4 is a detail section taken on line 4—4 of Fig. 1.

Fig. 5 is a detail section taken on line 5—5 of Fig. 1.

Fig. 6 is a detail section taken on line 6—6 of Fig. 1.

Fig. 7 is a top plan view of the lower sec-

tion or thickness of the double thickness board.

Fig. 8 is a top plan view of the board shown in Fig. 2.

5 Fig. 9 is a top plan view with the flaps unfolded, showing a body secured upon the board.

Fig. 10 is a view similar to Fig. 9, with certain of the flaps in folded position.

10 As shown on the drawings:

The reference numeral 1, indicates the bottom section or thickness of the mortuary board, and 2, the top section or thickness which is glued thereto or secured in any

15 other suitable manner. Recessed between said sections 1 and 2, at the front end of the board, is a reinforcement plate 3, having holes therethrough registering with hand holes 4, formed in said sections 1 and 2.

20 Similarly recessed between said sections 1 and 2, at the rear end thereof, is a reinforcement plate 5, provided with hand holes in register with hand holes 6, formed through said sections 1 and 2. Just beyond 25 the middle portion of the board, toward the forward end thereof, a transverse reinforcement or bracing bar 7, is recessed between the sections 1 and 2, to stiffen the same. A fabric covering, such as white glazed cloth

30 8, is secured over the top surface of the upper section 2, of the board, with its margin secured over the edges of the board. Also secured between said board sections 1 and 2, are fabric straps, two disposed at the forward end of the board denoted by the reference numerals 9 and 10, respectively, and two disposed near the foot of the board denoted respectively by the reference numerals 11 and 12. A binding strip 13, is se- 35 cured preferably by nickel headed nails, entirely around the peripheral edge of the associated board sections 1 and 2, and secured to the board thereby, are inner flaps 14, preferably of white glazed material, with

40 45 the glazed material adapted to fold inwardly, and outer flaps 15, preferably of black glazed fabric with the glazed surface on the exterior thereof when folded, and end flaps 16, of white glazed fabric 50 with the glazed surface on the interior when folded.

Disposed at the forward ends of the mortuary board, is a ring shaped rubber or other pneumatic head rest 17, held attached by a loop of fabric 18, which is secured by a screw 19, to the mortuary board, so that the head rest may be swung upwardly away from the board for cleaning purposes when desired.

60 The operation is as follows:

The body, as shown in Fig. 9, is laid upon the mortuary board with the head disposed upon the head rest 17, and the inner straps 10 and 12, respectively, are then buckled 65 over to hold the body securely upon the

board. The inner side flaps 14, are then folded over the body, and the end flaps 16, likewise folded inwardly, as shown in Fig. 10, after which the exterior side flaps 15, are folded inwardly over the folded flaps 14 and 16, in the manner shown in Figs. 2 and 8, and the exterior straps 9 and 11, buckled therearound. Thus a compact and easily handled element is afforded, and difficult passageways, doors, stairs, fire escapes 70 and the like may be easily negotiated in transferring the body.

We are aware that various details of construction may be varied through a wide range without departing from the principles 80 of this invention, and we therefore do not purpose limiting the patent granted otherwise than necessitated by the prior art.

We claim as our invention:

1. A mortuary board comprising two 85 thicknesses of material secured to one another, reinforcement means disposed therebetween, a plurality of straps secured between said thicknesses of material and extending on each side of the board, and flaps 90 attached on the sides and end edges of the board.

2. A mortuary board of the class described comprising two thicknesses of material, reinforcement means therebetween, double 95 flaps secured on each side edge of the board, and single end flaps secured on each end thereof.

3. A mortuary board of the class described comprising a board member, flaps connected 100 along the side and end edges thereof, straps to secure a body on the surface of the board member prior to folding the flaps thereover, and straps to be secured around the flaps on the exterior thereof after folding the same 105 over the body on the board.

4. A mortuary board of the class described comprising a board member built up of sections, flaps secured on the side and end edges thereof, reinforcement means disposed between the sections of which the board is built up, said board member having hand holes formed through said sections, and reinforcement means at each end of the built up board. 110

5. A built up mortuary board comprising a plurality of thicknesses of material, reinforcement means therebetween, straps secured between said thicknesses and extending on each side of the board, flap members 115 secured at each end and along the side edges of the board, and said board having hand holes formed at each end through the thicknesses thereof and through said reinforcement means.

6. In a device of the class described, board members secured one to another, reinforcement means disposed therebetween at each end and intermediate the ends thereof, a plurality of pairs of straps secured between 120 125 130

said board members, and flaps secured along the side and end edges of the associated board member.

7. A mortuary board of the class described comprising a board, reinforcement means disposed on the interior thereof, straps secured to said board, inner and outer side flaps secured to said board, there being two flaps on each side thereof, end flaps secured to the board, and a plurality of pairs of straps, one pair disposed to be strapped over a body laid upon the board, and covered by

said flaps folded thereover, and the other pair adapted to be strapped over the body on the exterior of the flaps folded thereover. 15

In testimony whereof we have hereunto subscribed our names in the presence of two subscribing witnesses.

RAYMOND L. KIRKPATRICK.
ANTHONY MOLTHEN.
